UNITED STATES PATENT OFFICE.

JAMES M. DODDRIDGE AND WILBUR I. DODDRIDGE, OF MILTON, INDIANA.

DESIGN FOR A LINING FOR GRAVES.

42,097.

Specification for Design.

Patented Jan. 16, 1912.

Application filed December 5, 1908. Serial No. 466,197. Term of patent 14 years.

To all whom it may concern:

Be it known that we, JAMES M. DODDRIDGE and WILBUR I. DODDRIDGE, both citizens of the United States, and residents of the town of Milton, in the county of Wayne and State of Indiana, have invented a new, original, and ornamental Design for a Lining for Graves, of which the following is a specification.

The accompanying drawing is an elevation showing a portion of a grave lining embodying our invention.

It will be noted that we actually provide

two distinct linings or a lining in two distinct parts—one for the upper and one for the lower part of the grave.

We claim—

The ornamental design for a lining for graves, as shown.

Signed at Milton, Wayne county Indiana, November 30, 1908.

JAMES M. DODDRIDGE.
WILBUR I. DODDRIDGE.
